UNITED STATES PATENT OFFICE.

JAMES JACKSON, OF GREGORY, MICHIGAN.

ELEVATOR SAFETY ATTACHMENT.

1,207,049.

Specification of Letters Patent.

Patented Dec. 5, 1916.

Application filed September 16, 1915. Serial No. 51,038.

To all whom it may concern:

Be it known that I, JAMES JACKSON, a citizen of the United States, residing at Gregory, in the county of Livingston and State of Michigan, have invented certain new and useful Improvements in Elevator Safety Attachments, of which the following is a specification.

My invention relates to the class of elevators, and more particularly to a safety appliance for preventing an elevator cage from dropping owing to the breaking of the suspending cable.

The primary object of my invention is to provide a safety device of the above character which is simple in construction, cheap to manufacture, strong and durable, and effective in operation.

Another object of my invention is to provide a safety device of the class above mentioned which may be applied to any of the existing types of elevators without altering the control mechanism of the elevator in any degree.

25 A further object of the invention is to provide a safety device for elevators which will quickly and positively engage the guides of the cage to prevent said cage from dropping.

With the above and other objects in view 30 my invention resides preferably in the construction, combination, and arrangement of parts as hereinafter set forth in the specification and illustrated in the accompanying drawings, in which—

35 Figure 1 is a vertical sectional view taken through an elevator shaft and cage showing my invention applied thereto and in unlocked position. Fig. 2 is a similar view showing the invention in a locked position.

40 Fig. 3 is a similar view taken on a plane at right angles to the plane on which Figs. 1 and 2 are taken.

Similar reference characters indicate similar parts throughout the various views of 45 the drawings.

In the drawings, wherein the preferred embodiment of my invention is illustrated, an elevator shaft is shown and designated 1. The walls of said shaft having the usual guides 2 thereon, said guides having wearing plates 3 on their outer faces. Screws 4 or the like serve to secure said plates and guides in position. The guides and plates are apertured as indicated at 5 for a purpose which 55 will hereinafter appear. An elevator cage is designated 6 and is provided with a top

wall 7 having a transverse beam 8 disposed thereon for a purpose which will hereinafter appear.

The device of my invention includes broadly a plurality of locking members for engagement in certain of the apertures 5, an operating frame therefor, and means for actuating said operating frame. The locking members include a plurality of slidably mounted oppositely movable bars 9 and 10, said bars being supported in guides 11 and 12, respectively, carried by the beam 8. The top wall 7 of the cage 6 may also serve as an additional guide for the bars 9 and 10. On the inner adjacent extremities of the bars 9 and 10 are disposed transverse pins 13 and 14, said pins being connected by a coil spring or the like 15 serving to maintain the bars in the position shown in Fig. 1.

The operating means of my invention includes a frame 7 having sides 16 and 17. The sides 16 and 17 are supported in spaced relation by means of blocks 18 disposed at desired points throughout the height of the frame. Suitable ribs 19 are provided on the sides 16 and 17 to assist in retaining the blocks in position, securing bolts 20 passing through said sides and beneath said blocks, whereby to maintain a rigid structure. As shown to advantage in Fig. 3 the frame embraces the beam 8, said beam having guiding recesses 21 cut in the opposite faces thereof to accommodate the sides 16 and 17 of said frame. A web plate 22 extends transversely of the frame and between the sides thereof, and is provided with a plurality of projections 23 for engagement in suitable openings in said sides. The web plate is provided with an aperture 24 in which a ring 25 may be received, said ring having connection with a hook 26 carried by the lower extremity of the supporting cable or the like 27. A plurality of bolts 28 are disposed in the sides 16 and 17 adjacent said web plate so as to prevent flexing of the plates under load, which would be undesirable.

On the inner faces of the sides 16 I have provided a plurality of substantially V-shaped cams 29 and 30, said cams engaging the opposite extremities of the transverse pins 13 and 14 for a purpose which will hereinafter appear. The cams project into engagement with said pins and also snugly engage the beam 8 so that the movement of the frame relative said beam will be even and free of lateral lost motion.

The actuating means of my invention includes a plurality of coil spring elements or the like 31 and 32 having their adjacent extremities connected at 33 to the web plate 22 and their opposite extremities connected at 34 and 35 to the beam 8. The springs are of the contractile type and exert a downward pull on the frame which is counteracted by the weight of the cage as long as the cable 27 remains intact.

The operation of my invention is as follows: Under normal conditions the frame, which is vertically slidable relative to said beam 8 is in the position shown in Fig. 1. The weight of the cage 6 exerts a downward pull on the springs 31 and 32 which in turn exert a similar pull on the frame F, but owing to the fact that the cable 27 is normally intact, the action of the cage and springs is neutralized. However, should the cable break or suddenly become free allowing the cage to drop rapidly the springs will be allowed to exert their force on the frame, moving the same from the position in Fig. 1 vertically into the position shown in Fig. 2. The inclined faces of the V-shaped cams 29 and 30 will engage the free extremities of the pins 13 and 14 causing their separation and thereby forcing the bars 9 and 10 into engagement with certain of the apertures 5 in the guides 2. This will effectively check the further descent of the cage. It is desired that it be understood that the peculiar form of beam shown in my invention may be altered to suit the condition existing in different types of elevators, and that the frame may also be altered for this purpose, it, of course, being understood that the changes are within the scope of the invention as claimed.

While I have shown and described my invention as possessing a peculiar form and construction, it is desired that it be understood that I may make such changes in the details thereof that do not depart from the spirit and scope of the invention as claimed.

Having thus described my invention what I claim and desire to secure by Letters Patent is:

50 1. A safety attachment for elevators, including a plurality of laterally slidable lock-

ing bars, a frame comprising spaced side members, operating means connected with said frame, and cams carried upon said side members and engageable with said bars whereby the same will be moved to locking positions upon failure of the cable.

2. A safety attachment for elevators, including a plurality of laterally slidable yieldably connected locking bars, pins on 60 said bars, a frame comprising spaced side members, spacing means therefor, spring actuating means connected with said frame, and cams carried upon said sides and engageable with said pins to move said bars to 65 locking position.

3. A safety attachment for elevators, including, in combination with an elevator shaft having apertured guides therein and a cage, laterally slidable locking bars for 70 engagement in said apertured guides, means for normally maintaining said bars in retracted positions, a frame comprising spaced side members, spacing means therefor, spring actuated means connected with said 75 frame, and cams carried upon said side members and engageable with said locking bars whereby to move the same to locking positions upon failure of the cable.

4. A safety attachment for elevators, including, in combination with an elevator shaft having apertured guides therein and a cage, a plurality of laterally slidable yieldably connected locking bars carried by the cage, pins on said bars, a frame comprising 80 spaced side members arranged upon said cage and movable with relation thereto, spacing means therefor, a top bar secured to said side members to facilitate connection with a cable, spring actuating means connected to said top bar and said cage for moving the frame and sides, and cams carried upon said side members engageable with said pins to move the locking bars into engagement with the apertured guides upon 95 failure of the cable.

In testimony whereof I affix my signature in presence of two witnesses.

JAMES JACKSON.
